CLAIM

The ornamental design for a door light, as shown and described.

DESCRIPTION

FIG. 1 is a top, front, right side perspective view of a door light showing my new design.

FIG. 2 is a front elevational view of the embodiment of FIG. 1;

FIG. 3 is a back elevational view of the embodiment of FIG. 1;

FIG. 4 is a left side elevational view of the embodiment of FIG. 1, the right side being a mirror image thereof;

FIG. 5 is a top plan view of the embodiment of FIG. 1, the bottom plan view being a mirror image thereof; and,

FIG. 6 is a top, front, right side perspective view of the door light of the embodiment of FIG. 1 in use with a frame.

The broken lines are for illustrative purposes only and form no part of the claimed design.

1 Claim, 2 Drawing Sheets
